CLAIM

The ornamental design for a flying car, as shown and described.

DESCRIPTION

Fig. 1.1 is a top, front, and left side perspective view of a flying vehicle where the wings are in a closed configuration, showing our new design;

Fig. 1.2 is a front elevation view thereof;

Fig. 1.3 is a rear elevation view thereof;

Fig. 1.4 is a left side elevation view thereof;

Fig. 1.5 is a top plan view thereof;

Fig. 1.6 is a bottom plan view thereof; and

Fig. 1.7 is a top, front, and left side perspective plan view thereof where the wings and the propeller are in the open configuration.

1 Claim, 7 Drawing Sheets
